United States Patent Office.

FREDERICK SHALLER, OF HUDSON, NEW YORK, ASSIGNOR TO HIMSELF AND JOHN B. LONGLEY, OF SAME PLACE.

Letters Patent No. 91,778, dated June 22, 1869.

IMPROVEMENT IN LAMP-BURNERS.

The Schedule referred to in these Letters Patent and making part of the same.

To all whom it may concern:

Be it known that I, FREDERICK SHALLER, of Hudson, in the county of Columbia, and State of New York, have invented a new and useful Improvement in Lamps; and I do hereby declare that the following is a full, clear, and exact description of the same, reference being had to the accompanying drawings, which form part of this specification.

This invention, though more especially designed for lamps adapted to the burning of kerosene, may also be applicable to other kinds of lamps.

It consists, first, in elastic bearing-straps, of novel construction, for supporting the journals of double feed-rollers, whereby provision is made for reception between said rollers of wicks of different thicknesses.

It consists, secondly, in an elastic chimney-holder, of novel character, whereby provision is made for the expansion of the chimney by heat.

Referring to the accompanying drawings—

Figures 1 and 2 represent vertical sections of a lamp-burner constructed according to my improvement, taken at right angles to each other; and

Figure 3 represents a plan view of the same, with the chimney and the burner-cap removed.

Similar letters of reference indicate corresponding parts in the several figures.

A represents the upper part, or neck of the reservoir of a kerosene-lamp, and upon which is fitted my improved burner.

The wick-tube B is of the ordinary construction, except that it is made to extend somewhat higher, for the purpose of lessening danger of explosion, by increasing the distance between the flame and the oil contained in the reservoir.

D is an annular support, or gallery, for sustaining the burner-cap, and is supported upon braces b, b, passing therefrom, and secured to the screw-cap E.

Between this ring, or gallery D, and the screw-cap, is formed an annular space, c, which serves as a better means of vent or ingress of air to the flame than the small perforations heretofore used for that purpose.

This annular space c may be of any breadth best suited to the size of the burner, and the degree of draught required.

C is a burner-cap, of conical, or tapering formation, and of a height proportionate to that of the wick-tube.

The base of this burner-cap is of suitable size for resting upon the face of the said gallery D, and is, or

may be retained thereon by means of springs, e e, attached thereto, and fitting in recesses, s s, made in the inner edge of the gallery, while, by its upwardly-tapering form, the air is more rapidly drawn up to the flame and around the heated parts.

By means of this new construction of burners, a much stronger draught is obtained than with burners of ordinary construction, thereby not only affording better light, by assisting combustion and saving oil by consumption of gases otherwise escaping, but also by the more rapid circulation of air in and around the heated parts of the burner, the temperature of said parts is reduced, thereby rendering the lamp less liable to explosion.

H is an elastic chimney-holder.

Said holder is composed of two pieces of elastic wire, which, having their corresponding extremities arranged near each other, are each secured by their opposite extremities to opposite sides of the gallery b, and, extending upwardly, and inclining toward each other, are made to cross at or about a point, z, and after crossing, are each bent outwardly in opposite directions, so as jointly to form a horizontal elastic ring for the reception of the chimney, their central portions being previously bent in a semicircular form for that purpose.

f f are curved elastic bearing-straps, attached to the screw-cap E, and having elongated bearing-openings in them, for reception of the journals of double feed-rollers, m m.

By means of said curved elastic straps, whose forms in their normal state are much more curved than when outwardly strained, as represented in the drawing, the said feed-rollers are not only held against the sides of the wick, but, by their yielding and contracting nature, provision is made for reception, between the rollers, of wicks of different thicknesses.

What I claim as my invention, and desire to have secured by Letters Patent, is—

1. The curved elastic bearing-straps f f, in combination with the double feed-rollers m m, substantially as and for the purpose herein set forth.

2. The elastic chimney-holder D, constructed as described, for the purpose herein set forth.

FREDERICK SHALLER.
